Primary Examiner — Sheryl Lane*Assistant Examiner* — Samantha N Wood(74) *Attorney, Agent, or Firm* — Sheppard Mullin; Daniel Yannuzzi; Jonathan Marina**CLAIM**

I claim the ornamental design for a handbag with a detachable internal bag, as shown and described.

DESCRIPTION

FIG. 1 is a top, left, and front side perspective view of an ornamental design for a handbag with a detachable internal bag;

FIG. 2 is a front side elevational view thereof;

FIG. 3 is a rear side elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a top, left, and front side perspective view of the handbag with a detachable internal bag, with the internal bag detached and removed.

The broken line showings of the stitching of the internal bag in FIGS. 1–4, 6, and 8 form no part of the claimed design. The broken line showings of the tabs, feet, zipper, internal buttons, and bottom panel of the handbag with a detachable internal bag in FIGS. 1–8 form no part of the claimed design.
